UNITED STATES PATENT OFFICE.

EDWARD WOTTON, OF NEW YORK, N. Y., ASSIGNOR TO FIFTH AVENUE COACH COMPANY, A CORPORATION OF NEW YORK.

FOLDING TOP FOR VEHICLES.

1,361,950.

Specification of Letters Patent. Patented Dec. 14, 1920.

Application filed November 17, 1919. Serial No. 338,580.

To all whom it may concern:

Be it known that I, EDWARD WOTTON, a subject of the King of Great Britain, residing at New York city, in the county of 5 New York and State of New York, have invented certain new and useful Improvements in Folding Tops for Vehicles, of which the following is a specification, reference being had therein to the accompanying drawing.

This invention relates to a folding canopy top for vehicles, and has reference more particularly to a folding top for motor busses, the object of the invention being to provide 15 a top which when opened and extended for use, will cover the seats on the top or deck of the bus and effectually protect the passengers from the weather, and which when in folded or closed position, will be stored in 20 compact form out of the way so as not to obstruct the passengers' space on the deck.

With this end in view, the invention consists of a top embodying two end bows and an intermediate bow, to which bows the 25 canopy is connected as usual, and the legs of which bows are adapted to be pivoted to the vehicle to permit them to be folded side by side, the legs of the intermediate bow being extensible to enable the bow to be lengthened when the top is folded, so that it may 30 be disposed even with the end bows and will not obstruct the passengers' space on the deck, and the end and intermediate bows being operatively connected together in such 35 manner that in the folding and unfolding of the top, the intermediate bow will be automatically lengthened and shortened.

The invention consists also in combining with a canopy top for the upper deck of an 40 omnibus, an end curtain connected respectively with the end of the canopy top and with the vehicle, and formed to partially close the end of the deck so that an opening will be left for the entrance and exit of the 45 passenger to and from the deck when the top is in an open operative position.

The invention consists also in the details of construction and combination of parts hereinafter described and claimed.

50 In the accompanying drawings:

Figure 1 is a front perspective view of an omnibus having my improved folding canopy top applied thereto and showing the same in open operative position.

Fig. 2 is a rear perspective view of the 55 same.

Fig. 3 is a front perspective view with the top in folded or closed position.

Fig. 4 is a perspective view showing how the folding operation is performed. 60

Fig. 5 is a side elevation on an enlarged scale of my improved top removed from the vehicle, a portion of the canopy being removed to better show the construction of other parts. 65

Fig. 6 is a cross section on the line 6—6 of Fig. 3.

Referring to the drawings:

My improved top comprises two end bows 1—1 and an intermediate bow 2, the two end bows consisting each as usual of the horizontal portion 1^a connected to and supporting the opposite ends of the canopy A, and the two parallel legs 1^b. The intermediate bow comprises a horizontal portion 2^a which 75 is connected to and supports the middle portion of the canopy, and the two parallel legs 2^b, which legs are extensible so that the bow as a whole may be lengthened and shortened relatively to the end bows for the 80 purposes presently to be described.

The ends of the legs of the three bows are pivotally connected together at each side, and are pivotally connected to the opposite sides of the vehicle so that they may be 85 folded from the open extended position as shown in Fig. 1 to the closed position shown in Fig. 3. It will be observed that in the open position of the top, the canopy is substantially horizontal, the legs of the end bows extending in opposite directions at angles of about 45°, from their lower ends to the ends of the canopy. The intermediate bow however, extends vertically to the canopy from the pivotal points of its legs. Due 95 to this condition, the intermediate bow is of considerable less length than the end bows, and while this condition is desirable in the open position of the top, since it enables the top to be horizontal and at the same time 100 gives sufficient height for the passengers to walk erect beneath, it is undesirable in the closed or folded position, since the horizontal portion of the short intermediate bow would extend inwardly of the end of the 105 passenger space on the deck and would obstruct this space. It is to obviate this condition that I make the legs of the interme-

dition that I make the legs of the interme-

diate bow extensible, and provide connections between the same and the end bows which will cause the intermediate bow to be lengthened or extended to the same position 5 when folded as the end bows, and thereby leave the space at the end of the deck free for the passengers.

The specific construction of the legs of the intermediate bow to effect this object is 10 shown more particularly in Figs. 1 and 4, where it will be seen that each of the legs 2^b comprises a tubular lower section 2^c and an upper section 2^d which fits slidably into the lower section and telescopes therein. 15 The two upper sections of the bow are connected fixedly together by means of the horizontal portion 2^e, and the two tubular lower sections are provided with longitudinal slots 3 in which extend pins 4 carried by the 20 upper sections, by which means the upper sections are guided in the lower sections and limited in their movements therein. The lower tubular sections are pivoted at their lower ends to the opposite sides of the frame 25 of the vehicle on aligned transverse axes formed by horizontal pivot bolts 5 which are extended through the ends of the two sections and into the frame of the vehicle; and the lower ends of the legs of the two 30 end bows are pivoted to the lower ends of the tubular sections on horizontal transverse axes 6 and 7. Due to this construction and arrangement of the parts, the three bows may be spread apart from each other in the 35 open position of the top as shown in Fig. 1, in which position the intermediate bow will extend in a vertical position and the two end bows will extend in opposite directions and at an inclination. In this position of 40 the parts, the intermediate bow is in its contracted shortened condition with the upper sections of its legs seated to their full extent in the tubular lower sections, and with the pins 4 at the lower ends of the slots 3. 45 From this position the bows may be folded back to the closed position shown in Fig. 3, and in such folded position of the parts, the intermediate bow may be lengthened by the movement of the upper sections of the legs 50 outwardly in the tubular lower sections, whereby the horizontal portion 2^a of the bow may be caused to align with the corresponding portions of the end bows.

In order that the intermediate bow may 55 be thus lengthened and shortened automatically by the operations of folding and unfolding the top, the legs of the two end bows are operatively connected with the upper sections of the intermediate bow in 60 such manner that when the bows are swung back and down to fold the top, the upper sections of the intermediate bow will be positively moved outwardly in the lower sections, and the intermediate bow will be thus 65 lengthened; and when the bows are swung

upwardly again to unfold and extend the top, the upper sections of the intermediate bow will be moved down again and telescoped into the lower sections and the bow thus shortened.

70

In the present instance, this action of the parts is effected by two pairs of connecting links 8, a pair on each side of the structure. Each pair comprises a link 8^a which is pivoted at one end to the leg of one end bow 75 as at 8^b and is pivoted at its opposite end as at 8^c to the upper section of the intermediate bow, and a link 8^d which is pivoted at one end to the other end bow as at 8^e and which is pivoted at its other end to the upper 80 section of the intermediate bow adjacent the connection of the link 8^a, as at 8^f. These links, when the bows are spread apart in the open position of the top, extend from their lower ends at an upward inclination 85 toward each other as shown in Fig. 1, it being understood that there is a pair of such links at each side of the top, the links of each pair being similarly connected with the corresponding parts at each side.

90

The upper deck of the vehicle to which my improved top is shown as applied, is surrounded by a railing X which incloses the passenger space containing the seats Y. These seats face forwardly along both sides 95 of this space in two rows, and they occupy the full length of the space from one end railing to the other. Consequently, it is necessary that the space be free at all times so that the passengers can pass to and from 100 the extreme end seats. The length of the end bows of my improved top is therefore such that when they are swung forwardly to folded position as shown in Fig. 3, their horizontal portions 1^a will not extend in 105 toward of the end deck railing and obstruct the passenger space. In the example shown, the length of the end bows is such that their horizontal portions will extend beyond said end railing, the links 8 being of such length 110 and so connected with the upper sections of the legs of the intermediate bow and to the legs of the end bows, that in the folding operation, the intermediate bow will be lengthened sufficiently so that its horizontal 115 portion 2^a will also pass beyond the end rail of the deck and will line up with the corresponding parts of the end bows when the parts are completely folded as shown in Fig. 3.

120

To hold the top in extended open position, I provide stay straps 10, two at each end, which straps have their upper ends connected with the respective end bows and are adapted at their lower ends to be fastened 125 to the deck railing.

In the particular form of bus shown in the drawings, the upper deck is reached by a stairway B leading from the rear end of the lower deck to a side entrance C at the 130

rear end of the upper deck. In order that when the top is in extended open position, the rear end of the deck may be closed against the weather without obstructing this 5 side entrance, I provide an end curtain 11 as shown in Fig. 2, which is fastened at its upper edge to the rear end of the top, and at its lower portion to the rear end railing. This curtain extends only part way around 10 the end of the deck, its inner edge terminating at the inner side of the entrance passage. As a result, the entrance passage is left open, while at the same time the remaining portion of the end of the deck is effectually closed. 15

The front end of the deck is closed by a front curtain 12 which is connected at its upper end to the forward end of the canopy top and at its lower end to the front end railing. 20

In the operation of folding the top, it is only necessary to release the rear stay straps and push back on the legs of the end bows. The conductor then takes hold of the stay 25 straps and allows the bows to fold down by gravity as shown in Fig. 4. As the bows thus swing back, the pairs of links 8 will thrust up on the upper sections of the extensible legs of the intermediate bow, and will 30 lengthen the same automatically, and as the several bows approach each other and reach their complete folded position as shown in Fig. 3, they will all be in alinement with each other and disposed beyond the front 35 end railing and free of the passenger space.

As a means for further supporting the flexible canopy at points between the end and intermediate bows, I provide two supplemental bows, one 13 at the front, and the other 14 at the rear. The front supplemental bow has its legs pivoted to the legs of the forward end bow and extends at an upward inclination toward the rear and has its horizontal portion 13^a connected with 40 the canopy about midway between the horizontal portions of the intermediate bow and the front end bow. The rear supplemental bow 14 has its legs pivoted to the upper sections of the legs of the intermediate bow, 45 and it extends rearwardly therefrom at an upward inclination and has its horizontal portion 14^a fastened to the canopy at a point midway between the horizontal portions of the rear bow and the intermediate bow. 50 These supplemental bows will fold back 55 with the intermediate bow and the front end bow, and they are of such length that when the several bows are folded, their horizontal portions will line up with the corresponding 60 portions of the other bows.

Having thus described my invention, what I claim is:

1. In a folding top for vehicles, the combination of end bows and an intermediate bow, said bows having their legs pivotally 65

mounted to fold together, the intermediate bow being extensible so that it may be lengthened when folded, and means actuated by the pivotal movement of the bows in the folding operation, for lengthening 70 the intermediate bow.

2. In a folding top for vehicles, the combination of end bows and an intermediate bow, said bows having their legs pivotally mounted to fold together, and the intermediate bow being extensible so that it may be lengthened when folded and shortened when unfolded, and means actuated by the pivotal motions of the bows in the folding and unfolding operations for positively 80 lengthening and shortening respectively said intermediate bow.

3. In a folding top for vehicles, the combination of end bows and an intermediate bow, said bows having their legs pivotally mounted to fold together, and the said intermediate bow being extensible in length, and members connecting an end bow with the intermediate bow and arranged to lengthen and shorten the intermediate bow 90 in the pivotal movements of the end bow in the folding and unfolding operations.

4. In a folding top for vehicles, the combination of end bows and an intermediate bow, said bows having their legs pivotally mounted to fold together, and the said intermediate bow being extensible in length, and members connecting the two end bows with the intermediate bow and arranged to lengthen and shorten the intermediate bow 100 in the pivotal movements of the end bows in the folding and unfolding operations.

5. In a folding top for vehicles, the combination of end bows and an intermediate bow, said bows having their legs pivotally mounted to fold together, and the legs of said intermediate bow being extensible so that the bow may be lengthened and shortened, and members connecting the legs of the end bows with the legs of the intermediate bow, said members arranged to automatically extend the intermediate bow 110 when the bows are folded together.

6. In a folding top for vehicles, the combination of end bows provided with legs pivotally mounted, an intermediate bow provided with legs comprising lower sections pivotally mounted adjacent the legs of the end bows, and upper sections slidably connected with the lower sections, and links pivoted at one of their ends to the legs of the end bows and pivoted at their other ends to said upper sections of the intermediate bow, said links when the top is in unfolded extended position, extending 120 upwardly at opposite inclinations toward each other.

7. In a folding top for vehicles, the combination of end bows provided with legs, an intermediate bow provided with legs 130

comprising lower sections pivotally mounted and upper sections slidingly connected with the lower sections, the ends of the legs of the two end bows being pivoted to said lower sections adjacent the pivotal axes of said sections, and two links pivoted at their lower ends to the legs of the end bows and extending upwardly at opposite inclinations toward each other and pivoted at their upper ends to the upper section of the intermediate bow.

8. In combination with a vehicle having an upper open deck inclosed by side and end railings and containing seats for the accommodation of passengers, a folding top for said deck consisting of end and intermediate bows pivotally mounted on the vehicle to fold together, the said end bows being of sufficient length to extend to or beyond the end rail of the deck when folded, and the intermediate bow being of less length than the end bows when the top is in extended open position, and said intermediate bow being extensible in length, and members connecting the two end bows with the intermediate bow and arranged to automatically lengthen and shorten the inter-

mediate bow in the pivotal movements of the end bows in the folding and unfolding operations; whereby when the top is folded, 20 the intermediate bow will be caused to extend beyond the passenger space.

9. In combination with an omnibus having a lower deck and an upper deck, end and side rails inclosing the upper deck, one 25 of said end rails terminating at one end a short distance from the end of the side rail to leave an entrance passage to the deck at one side for the entrance of passengers, stairs leading from the lower deck to said 40 entrance passage, a top extending over the deck, and a curtain for closing the end of the deck containing the entrance passage, said curtain being connected at its upper end to the top and at its lower end to the 45 end deck railing and extending from the side of the deck toward the entrance passage and terminating at its inner end at the inner side of said passage; whereby the end of the deck will be closed without obstructing the entrance passage.

In testimony whereof, I have affixed my signature hereto.

EDWARD WOTTON.
